PULSE TRANSMISSION SYSTEM

Walter Emil Wilhelm Jacob, Hagersten, Sweden, assignor to Telefonaktiebolaget L M Ericsson, Stockholm, Sweden, a corporation of Sweden

Filed Aug. 13, 1958, Ser. No. 754,758

Claims priority, application Sweden Aug. 29, 1957
4 Claims. (Cl. 179—15)

The present invention refers to a pulse transmission system for improving the efficiency when transmitting energy from a transmitter to a receiver.

In electronic telephone systems the different switching devices in the speak paths are often used for several simultaneous communications. Usually a time divided multiplex system is used, where the pulses are modulated in a known way. Usually the pulses have constant time position and duration, while the amplitude is modulated. In its simplest form such a pulse transmission system consists of a number of subscribers' stations, which each via a contact are connected to a common transmission medium. The contacts pertaining to a certain connection between a calling and called subscriber are cyclically closed during the time interval of each period allotted to the connection in question. The information signals are thus passing the common speak path as mutually time displaced modulated pulses. A low pass filter is connected between the subscriber and his contact. This filter, or more exactly, its terminating condenser turned against the contact operates as an energy accumulator, which accumulates energy during the pauses between the consecutive pulses. In order to improve the efficiency when transmitting energy from the transmitter, it is known e.g. through Ericsson Review No. 1, 1956, page 10, to connect an inductance between the low pass filter and the contact. This inductance is so dimensioned that it together with the terminating capacity of the low pass filter forms a tuned circuit, the period of which is equivalent to twice the contact make time. In this way the wave form of the current pulse, which transmits energy from the transmitter to the receiver is favourable, and as a matter of fact the whole energy will be transferred.

In practice difficulties are, however, found how to utilize the known device mentioned above, especially when building up a system having a great number of electronic contacts, as required in an electronic telephone system. With an increasing number of contacts the common transmission medium will get an increasing geometric extent so that its capacity to earth cannot be neglected. The electronic contacts have also certain leakage capacities, which are added to the earth capacity of the transmission medium. During energy transmission between the transmitter and the receiver this resulting earth capacity will be charged and for preventing cross-talk it must be discharged between the pulses, which, of course, causes an attenuation.

According to the invention the disadvantages of earth capacities can be avoided by a pulse transmission system, where the information signals of the individual connections are transmitted from a terminal to another via a transmission medium common to the connections as modulated pulses, and where the transmission medium is connected to each terminal via a contact, an inductor coupled in series to the contact, and a low pass filter, the terminals of which turned against the inductor are terminated by a condenser, which together with the inductor forms a tuned circuit, the resonance period of which is substantially equal to twice the time, during which the contacts are closed for transmitting a pulse. The invention is characterized by a capacitive circuit being connected between the common transmission medium and the generally grounded terminal of the low pass filter tuned

2

against the transmission medium, which pole is not connected to the inductor, said circuit having together with the common earth capacities of the transmission medium and the contacts connected to the same such a value that it together with said inductors and said condensers forms a tuned circuit with a resonance frequency, which is an even multiple of the resonance frequency of the first mentioned resonance circuit.

The invention will be more detailed described in connection with attached figures, where,

FIG. 1 shows a simplified schematic diagram of a known pulse communication station,

FIG. 2 shows a simple equivalent circuit illustrating the principle of the invention,

FIGS. 3 and 4 show voltage and current wave forms at a certain dimensioning of the device according to the invention,

FIGS. 5 and 6 show voltage and current wave forms at another dimensioning, while

FIG. 7 shows equivalent circuit with the subscribers divided in groups, which may be mutually connected.

In FIG. 1 the transmitter, which in an electronic telephone system comprises a subscriber's apparatus or a line, is supposed simplest to consist of a direct current source

25 V having the internal resistance R_s . The receiver, which in practice consists of the subscribers' apparatus just receiving, has the internal resistance R_m , which in a known way is to be equal to the internal resistance R_s of the current source V. In the transmission path there are 30 two low pass filters LP_s and LP_m on the transmitting and the receiving side, respectively. The filters LP_s and LP_m are matched to the internal resistance R_s and the load resistance R_m , respectively, and their terminals turned against the transmission path are terminated by the condensers C_s and C_m , respectively. The specific pulse transmission system is located between the two condensers C_s and C_m , said pulse transmission system consisting of two contacts K_s and K_m , which cyclically during relatively short time intervals connect the transmitter to the receiver over a common transmission medium T. Usually several transmitters and receivers are connected to this transmission medium.

An inductor, L_s respectively L_m , is connected between each contact and the pertaining low pass filter as well on 45 the transmitter as on the receiver. The inductors L_s and L_m form together with the condensers C_s and C_m , respectively, a tuned circuit, which in a known way is so tuned that the resonance period is equal to twice the time, during

50 which the contacts are closed for the cyclical interconnection of the transmitter and the receiver, i.e. the impulse time. By dimensioning the tuned circuits in this way the whole charge difference between the condensers C_s and the condenser C_m is transferred from the condenser

55 C_s to the condenser C_m during the time when the pertaining contacts K_s and K_m are closed. That also means that the voltage states prevailing across the condensers C_s and C_m immediately before closing the contacts, have changed place, when the contacts are opened again.

If bilateral contacts are used, it is possible to transmit 60 energy in both directions, i.e. the transmitter can also operate as a receiver, which is the case in usual telephone systems. The device is thus a two-wire communication system, which by using rapid electronic contacts is suitable for speak transmission in an electronic telephone exchange.

65 For speak transmission a switching frequency (pulse repetition frequency) of 8000–10000 Hz. is selected and the cut off frequency of the low pass filter is selected somewhat less than half the pulse repetition frequency. The cut off frequency and the impedance of the filters define the size of the condensers C_s and C_m , and therefore the inductance of the coils L_s and L_m is settled 70 by the selected contact close time.

When using a device according to FIG. 1 in practice certain difficulties will arise, especially if a great number of transmitters and receivers are connected to the common transmission medium, which for instance is the case in electronic telephone systems.

When the number of subscribers is great, the geometric extent of the transmission medium T will, however, be so large that its capacity to earth cannot be neglected. Also the contacts K_s and K_m connected to the transmission medium T have certain capacities, which are added to the above mentioned capacity. All these capacities can be joined together in the capacity shown in FIG. 1.

Under suitable circumstances, when C_j is negligible, the voltage of the transmission medium T is equivalent to half the sum of the voltages across the condensers C_s and C_m during the time the contacts are closed and a pulse is transmitted. As soon as the leakage capacity C_j is added, the voltage wave form during the pulse is superimposed by an oscillation, which arises between the capacities C_s and C_j on one hand and between the capacities C_m and C_j on the other hand. It may happen that the voltage between the transmission medium T and earth and therewith across the condenser C_j has a high value at the end of the transmission pulse. Some part of the energy, which should have been transmitted from the condenser C_s to C_m or conversely, therefore remains in the condenser C_j , from which it must be removed through a short circuiting contact K_t for preventing the charge from appearing in next pulse channel, where it would cause a considerable cross talk. The tap of a part of the information carrying energy means on the other hand that the transmission pulse is attenuated and the efficiency of the connection is decreased.

According to the invention such an injurious rest charge is prevented by connecting further a capacity between the transmission medium T and the earth which together with the earth capacity C_j to form a capacity C_t between the transmission medium T and earth. This capacity C_t is so dimensioned that the above mentioned oscillation gets such a waveform that the voltage of the transmission medium is zero or at least has a minimum at the end of the pulse. This occurs if the current through the condenser C_t has a frequency, which is an even multiple of the resonance frequency of the tuned transmission circuit formed by the circuit elements C_s , L_s , L_m , C_m , i.e. if the resonance frequency for the elements C_s , L_s , L_m , C_m , is f , the frequency of the superimposed oscillation across C_t is equal to $2n.f.$, where n is an integer. In practice only small values of n , e.g. 1 and 2, can, however, be used, as C_t will be small with an increasing value on n .

For a more detailed explanation of the operation reference is made to FIG. 2, which is a simplified equivalent diagram for a pulse transmission device. The capacity C_t is supposed to be divided in two equal condensers

$$\frac{C_t}{2}$$

and moreover is presumed that $C_s = C_m = C$ and that $L_s = L_m = L$. The value of the condenser

$$\frac{C_t}{2}$$

is equal to

$$\frac{C}{a}$$

According to the above it is supposed that the tuned circuit, which contains the condenser C and

$$\frac{C}{a}$$

in series with L has a resonance frequency, which is $2n$ times larger than the tuned circuit, which contains only C and L . This means that

$$\text{i.e. } a = 4n^2 - 1$$

and

$$C_t = \frac{2C}{4n^2 - 1} \quad (1)$$

Suppose that the condenser C_s is charged to a voltage V , while the voltages across the condensers

$$\frac{C_t}{2}$$

and C_m is zero. When the contacts K_s and K_m are closed, the charge of the condenser C_s is transferred to the condenser C_m in a course, which can be divided in the following superposed courses:

(A) A current pulse goes from C_s over L_s , K_s , K_m and L_m to C_m . This pulse is a half sinusoidal wave, i.e. it has the same shape as if the capacity should be zero.

(B) Two pulses consisting of one or several half sinusoidal wave at the same time transfer energy from C_s and C_m to C_t and back again to C_s or C_m , respectively. The output voltages across the capacities C_s and C_m are both the same and have the value

$$U_t = \frac{V}{2}$$

It can be easily shown by an energy discussion that the peak value I for the current pulse according to point A above will be

$$I = \frac{V}{2} \sqrt{\frac{C}{L}} \quad (2)$$

For estimating the behaviour of the current according to point B it is sufficient to study only one side of the transmission system e.g. the current in the elements C_s , L_s , K_s and the left half

$$\frac{C_t}{2}$$

of the capacity C_t . Supposing that the condenser C_s is charged to the voltage $V/2$ by studying the charges in the circuit, the following expression on the peak to peak value of the voltage U_t of the transmission medium when the current is zero after a half period of the progress according to B is obtained.

$$U_t = \frac{V}{4} \left(4 - \frac{1}{n^2} \right) \quad (3)$$

By an energy discussion of the same kind which resulted in the Equation 2 the following expression for the peak value I for the current wave according to B is obtained.

$$I = \frac{V}{4n} \sqrt{\frac{C}{L}} \quad (4)$$

As the connection generally is bilateral, the voltage across the condenser C_m is in practice not zero in the first moment of a transmission pulse, as the receiver at the same time acts as a transmitter and vice versa. On the common transmission medium the voltage is on the other hand equal to zero before a transmission pulse, as means are provided for short circuiting the transmission medium to earth in the pause between two channel pulses in order to remove possible rest charges.

Under these circumstances it is easily understood that the expressions for currents and voltage can be generalized. Of course the difference between the voltages V_s and V_m across C_s respectively C_m will determine the occurrence according to A, i.e. V will be replaced by $V_s - V_m$ in the Equation 2. On the other hand half of

the sum of the voltages V_s and V_m will determine the occurrence according to B, i.e.

$$\frac{V}{2}$$

will be replaced by the expression

$$\frac{V_s + V_m}{2}$$

in the Equations 3 and 4.

The earlier shown equations for the currents according to (A) respectively (B) above will become

$$I = \frac{V_s - V_m}{2} \sqrt{\frac{C}{L}} \quad (2a)$$

$$i = \frac{V_s + V_m}{4n} \sqrt{\frac{C}{L}} \quad (4a)$$

The transmission pulse is thus a superposition of half sinusoidal pulse with the amplitude

$$\frac{V_s - V_m}{2} \sqrt{\frac{C}{L}}$$

and a pulse consisting of n full sine waves with the amplitude

$$\frac{V}{4} \sqrt{\frac{C}{L}}$$

where n is an integer. On the transmitting side the pulses are added, while they are subtracted on the receiving side, as the half sinusoidal current pulse in the transmitting circuit has another sign than in the receiving circuit. The instantaneous value I_s of the transmission current pulse on the transmitting side will thus be:

$$I_s = \frac{1}{2} \sqrt{\frac{C}{L}} \left(\frac{V_s + V_m}{4n} \sin 2n\alpha + (V_s - V_m) \sin \alpha \right) 180^\circ \quad (5)$$

and the corresponding value on the receiving side will be

$$I_m = \frac{1}{2} \sqrt{\frac{C}{L}} \left(\frac{V_s + V_m}{4n} \sin 2n\alpha - (V_s - V_m) \sin \alpha \right) 180^\circ \quad (6)$$

in these equations α signifies the current angle of the pulse.

The voltage of the common transmission medium is only determined by the current according to (B) and the voltage drop across the capacity C_t of the transmission medium to earth. As the current according to (B) consists of n full sine waves, the voltage U_t of the transmission medium will vary according to n full periods of a cosine function, the peak to peak value of which is varying between zero and a value

$$U_t = \frac{V_s + V_m}{4} \left(4 - \frac{1}{n^2} \right) \quad (3a)$$

If $n=1$ is selected, the capacity C_t shall be

$$\frac{2C}{3}$$

according to Equation 1 and if the voltage V_m of the receiving side is supposed to be zero at the starting of the transmission pulse, the following instantaneous values of the current I_s and I_m are obtained.

$$I_s = \frac{V}{2} \sqrt{\frac{C}{L}} \left(\frac{1}{2} \sin 2\alpha + \sin \alpha \right)$$

$$I_m = \frac{V}{2} \sqrt{\frac{C}{L}} \left(\frac{1}{2} \sin 2\alpha - \sin \alpha \right)$$

The voltage U_t will be a cosine function having two full periods and a peak to peak amplitude varying between 0 and $1\frac{5}{16}$ v.

The currents I and i and the currents I_s and I_m ob-

75

tained by superposition the first mentioned currents on the transmitting and receiving sides respectively are shown for $n=1$ in Fig. 3 and for $n=2$ in FIG. 5. The voltage U_t on the transmission medium T is shown for $n=1$ in FIG. 4 and for $n=2$ in FIG. 6.

FIGS. 4 and 6 show that the voltage of the common transmission medium is zero at the end of the transmission pulse, i.e. no energy is left in the capacity C_t , if this capacity is

$$C_t = \frac{2C}{4n^2 - 1}$$

where n can be the integers 1, 2 . . .

If communication between more than two circuits e.g. 15 3 or 4 is desired in the same channel, the capacity must of course be increased to

$$\frac{3C}{4n^2 - 1}$$

20 respectively

$$\frac{4C}{4n^2 - 1}$$

or generally

$$\frac{P.C}{4n^2 - 1}$$

25 where P is the number of circuits, which are connected to the same channel. Such cases are, however, not very common within the telephone technic.

In great electronic telephone stations the subscribers' 30 circuits are generally divided in several groups, and each such primary group is over electronic contacts available for several secondary groups, to which trunk circuits are connected. FIG. 7 shows a diagram of such a connection. The subscriber circuit Ab is over the contact K_s 35 connected to the transmission medium T_{prim} of the primary circuit. The primary transmission is over an electronic group contact K_g connected to a secondary transmission medium T_{sek} , to which a circuit L_r is connected via a contact K_m . The capacities C_{prim} and C_{sek} 40 respectively of the two transmission media to earth are suitably so selected that

$$C_{prim} = C_{sek} = \frac{C}{4n^2 - 1}$$

45 Generally a primary subscriber group is larger than a secondary line group. It can be advantageous to make C_{prim} larger than

$$\frac{p.C}{4n^2 - 1}$$

50 and C_{sek} in the corresponding degree smaller so that

$$C_{prim} + C_{sek} = \frac{2C}{4n^2 - 1}$$

55 I claim:

1. In a multiplexing communication system comprising a plurality of subscriber stations, each having transmitting and receiving means connectable to an electrical transmission medium through an energizable switching means, said transmitting and receiving means including a first resonant circuit connected between two terminals of said transmitting and receiving means and one terminal of the electrical transmission medium through said switching means, said resonant circuit being resonant to a frequency corresponding to a period of time which is substantially twice the pulse time said switching means is energized and connects said transmitting and receiving means to said medium, the improvement comprising, in combination, a capacitive circuit electrically connected between said transmission medium and one of said two terminals, said capacitive circuit together with said first resonant circuit forming a second resonant circuit during pulse times said switching means is energized, said second 60 resonant circuit being resonant to a frequency substantially

7
tially an even multiple of the resonant frequency of said first resonant circuit.

2. In a multiplexing communication system comprising a plurality of subscriber stations, each having transmitting and receiving means connectable to an electrical transmission medium through an energizable switching means for communicating between said stations, said transmitting and receiving means including a first resonant circuit having a first capacitor shunt connected across terminals of said transmitting and receiving means and an inductance means serially connected between one side of said capacitor and one terminal of said switching means, said first resonant circuit being resonant to a frequency corresponding to a period of time which is substantially twice a period said switching means is energized and connects said transmitting and receiving means to said transmitting medium, the improvement comprising, in combination, a capacitive circuit electrically connected to another terminal of said switching means at one side thereof and to a common electrical potential for said system at another side thereof, said capacitive circuit together with said first resonant circuit forming a second resonant circuit during pulse times said contact is energized, said second resonant circuit being resonant to a frequency substantially an even multiple of the resonant frequency of said first resonant circuit.

3. In a multiplexing communication system as described in claim 2 for interconnecting at least two of said plurality of stations through said transmission medium for communication therebetween, the capacitance of said capacitive circuit being equivalent to

$$\frac{C \cdot p}{4n^2 - 1}$$

where C is the capacitance of said shunt-connected capac-

itor, n is an integer and p is the number of stations connected to the transmission medium.

4. In a multiplexing communication system comprising a plurality of subscriber stations each having transmitting and receiving means, a plurality of transmission mediums for electrical energy, at least one of said plurality of stations being operably connected to one of said mediums through an energizable contact means having several terminals connected to said mediums for electrically interconnecting stations connected to said mediums through said contact means, said transmitting and receiving means including a first resonant circuit having a capacitor shunt connected across terminals of said transmitting and receiving means and an inductance means serially connected between one side of said shunt capacitor and a terminal of said contact means, said first resonant circuit being resonant to a frequency substantially twice the period said contacts are energized to electrically interconnect said transmitting and receiving means to said mediums, the improvement comprising, in combination, a capacitor electrically connected to a capacitor electrically connected to each transmission medium and forming a second resonant circuit together with said first resonant circuit of a subscriber station connected to the same transmission medium during pulse times when said contact means is energized, said second resonant circuit being resonant to a frequency substantially an even multiple of the resonant frequency of said first resonant circuit.
